UNITED STATES PATENT OFFICE.

DENNIS E. LAHEY, OF LOUISVILLE, KENTUCKY.

RAILWAY SWITCH.

Application filed August 14, 1922. Serial No. 581,803.

To all whom it may concern:

Be it known that I, DENNIS E. LAHEY, a citizen of the United States, residing at Louisville, in the county of Jefferson and

5 State of Kentucky, have invented certain new and useful Improvements in Railway Switches, of which the following is a specification.

The present application is in part a continuation of my copending application 10 567,885, filed June 10, 1922.

This invention relates to improvements in railway tracks and particularly to railway switches.

15 The primary object of the invention is to so construct the trackage at the place where the switch is located that the tracks will be rendered safe and there will be no likelihood of a wreck occurring at this point.

20 A further object of the invention is to provide improved guard rails adapted to cooperate with the stock rails in such manner that the flanges of the car wheels will automatically throw the switch completely,

25 providing the switch has not been thrown its entire distance by the operator. These guard rails are also so constructed that they will house the switch points when the latter are not cooperating with the guard rails,

30 and owing to this, loose parts hanging from a train will not catch on the switch points and cause dislodgment of the same. The guard rails are provided with special cover plates designed to facilitate the passage of

35 articles hanging from the train over the same so that there will be no liability of a hanging part catching on a guard rail and tearing the same away from the ties.

A still further object of the invention is 40 to furnish improved ramps adapted to be placed between the stock rails and guard rails and designed to guide hanging parts through the throats formed between the guard rails and the stock rails. These ramps also function as filler blocks to space

45 the guard rails from the stock rails.

The present invention also includes special means for spacing the guard rails, and other specially designed parts for tying 50 the guard rails to the stock rails in order to prevent spreading of these members.

The entire construction of the present invention has been specially designed to eliminate defects in trackage, which have heretofore caused numerous accidents and wrecks.

The invention is illustrated in the accompanying drawings and will be more particularly described hereinafter.

Referring to the drawings:—

Figure 1 is a top plan view of a portion 60 of a railway track at the place where the switch points are located.

Fig. 2 is a transverse vertical sectional view of a portion of said track taken on the line 2—2 of Fig. 1. 65

Fig. 3 is a similar view taken on line 3—3 of Fig. 1.

Fig. 4 is a transverse sectional view taken on line 4—4 of Fig. 1.

Figs. 5 and 6 are similar views taken on 70 lines 5—5 and 6—6, respectively, of Fig. 1.

Fig. 7 is a perspective view of one of the cover plates of a guard rail.

Fig. 8 is a similar view of the guard rail.

Fig. 9 is a perspective view of a spacing 75 member that is adapted to be placed between the guard rails for holding the same apart.

Fig. 10 is a clamp used in connecting one of the guard rails to one of the stock rails. 80

Fig. 11 is a wedge-shaped key used with said clamp.

Fig. 12 is a horizontal sectional view of a detail showing the ramp or filler block in position. 85

Fig. 13 is a perspective view of one end of a switch point showing the same provided with a post adapted to support the electric wiring employed in a signaling system.

Fig. 14 is a top plan view partly in section of one of the guard rails shown on a reduced scale. 90

In the drawing, 1 and 2 designates the stock rails which are mounted in the usual manner upon ties 3 and cooperate with 95 switch points 4 and 5, which are pivotally connected as shown at 6 and 7 to one of the stock rails and to one of the switch rails.

Arranged between the stock rails is a 100 spacing member 8 adapted to hold the guard rails 9 and 10 in spaced relation. This spacing member is best shown in Fig. 9 and it consists of a rectangular bar 11 provided with apertures 12 adapted to receive the 105 bolts used in securing the same to one of the ties. The end portions 13 are arranged at a higher plane than the main portion of the bar 11 in order to engage the flanges 14 at the lower end of the guard rails as 110

shown in Fig. 4. From the raised portions 13, the ends of the bar extend vertically as shown at 15 for the purpose of engaging the vertical portion or web 16 of the guard rail. The upper end of the vertical portion 15 merges into an inwardly extending horizontal portion 17 that terminates in a vertically extending flange 18. As best shown in Fig. 4 the portion 17 is adapted to lie beneath the head 19 of the guard rail 9, while the flange 18 is designed to engage the inner edge of the head 19 and to extend upwardly above said head as shown. The portions 14 and 17 Fig. 9 of the spacing member are provided with apertures 20 adapted to receive bolts used in securing said member to the guard rail. The member 8 has vertical reinforcing webs 8^a at its ends.

Two guard rails are employed in the present construction and they are substantially similar in construction, with the exception that one is formed to cooperate with the switch point 4 while the other is shaped to cooperate with the switch point 5. Each guard rail, as best shown in Fig. 8, consists of a base 14 provided with apertures 21 to receive spikes used in connecting the same to the ties. From this base rises the web 16 which has an offset portion 22 adapted to be engaged by the switch point in a manner hereinafter described. The head 19 of the guard rail has holes 23 for a purpose hereinafter described. At this point it is to be noted that the offset portions 22 of the guard rails are to be set in directions parallel to the thrown positions of the switch points, in order that each switch point may snugly engage the offset portion of the guard rail.

It will be noted that the upper edge of each guard rail is tapered downwardly from the head 19 to the ends 24, as shown at 25.

Each guard rail is provided with a cover plate 26 having a horizontal portion 27 provided with apertures 28. Bolts or the like are adapted to be passed through the apertures 28 and 23 for the purpose of securing the plates to the guard rails. From the horizontal portion 27, the ends of the plate are tapered downwardly to correspond with the tapered edges 25 of the web 16, and owing to this tapered or sloping form of the plate, any parts hanging from the train and contacting with said plate will be guided over the plate as the train passes. The plate 26 terminates at one end in an inwardly extending flat portion 29 having holes 30 adapted to receive spikes 31 used in securing the same to one of the ties. The end portion of the plate 26 gradually merges into the portion 29 as shown at 32, and this provides a thickened portion which reinforces the plate. The opposite end of the plate 26 terminates in a rectangular portion 33 having apertures 34 to receive tie bolts 35. An up-

wardly extending curved portion 36 projects from one edge of the portion 33, and this portion 36 provides a space 37 as shown in Fig. 2, adapted to permit the base 38 of one of the switch points to move beneath the plate 26. It is to be especially noted from Fig. 1 that the free ends 39 of the portions 36 are tapered in order that parts hanging from a train may readily pass these edges without being caught by sharp corners and the like.

The outer edge of the plate 26, as best shown in Figs. 3, 4 and 5, is tapered downwardly at 40, and this tapered surface tends to guide the wheel flanges toward the stock rails and to prevent any hanging parts from catching on the plates 26.

It will be noted from Fig. 3 that the plate 26 projects outwardly beyond the web 16 of the guard rail, in order that the switch point 4 may move beneath said plate when the switch point is not cooperating with the stock rail. It will thus be seen that the plate 26 protects the switch point and prevents the same from being engaged by a wheel flange, as the train moves over the switch. This construction also prevents parts hanging from the train from being caught by the switch point. Owing to the guard rails being provided with the offset portions 22, a shoulder 41 will be provided on each guard rail intermediate its ends, and when a switch point engages one of the guard rails, the end of the switch point will lie in close proximity to said shoulder. Consequently, there will be no likelihood of any part being caught by the end of the switch point.

Arranged between each guard rail and the stock rail with which it cooperates, is a ramp or filler block 42, best shown in Figure 12. This member consists of a vertical flange 43 adapted to engage the underside of the head and a portion of the web of one of the stock rails as shown in Figs. 4, 5 and 6. The ends of this flange as shown in Fig. 12, are outwardly tapered at 44 for the purpose of facilitating the passage of hanging parts past the filler block. The filler block has a second flange 45 also provided with tapered ends or edges 46, as shown in Fig. 12. The portion of the filler block which lies between the flanges forms the bottom of a groove 47, and this bottom has its end portions tapered downwardly as shown at 48 for the purpose of guiding parts hanging from the train through the groove or throat. The block 42 is secured in place by means of bolts 49, and the upper edge of the flange 45 engages the underside of the outer edge of the plate 26 as shown in Fig. 4. It will be noted that the outer surface 50 of the flange merges into the surface 40 in order to facilitate the passage of hanging parts over these surfaces.

In order to secure a stock rail, a filler

block and a guard rail together, and to prevent relative spreading of these parts, I have provided substantially U-shaped clamps 51, best shown in Figs. 5, 10 and 11. Each of 5 these clamps is provided with a horizontal surface 52 adapted to contact with the base of the stock rail and the base of the guard rail. The clamp is also provided with a step-shaped surface 53 adapted to coact with 10 the head of guard rail and with the inner edge of the plate 26. The clamp is also provided with a vertically arranged surface 54 having a groove 55. The space between the surfaces 53 and 54 is slightly wider than the 15 combined thickness of the parts which are placed between the same, and this is to permit the insertion of a wedge key 56 having a projecting rib 57 adapted to slide in the groove 55.

20 As shown in Fig. 13, the end of the web of the switch point may be provided with a post 58 to permit the electric wiring used in a signaling system to be connected to the switch point. As the post arranged at the 25 end of the web might have a tendency to catch on to parts hanging from the train, I believe it preferable to arrange said post on the underside of the base of the switch point as shown in dotted lines and designated 59. 30 The switch points are connected together for joint movement by means of tie bars 60, and an operating bar 61 also connects the switch points. To permit the passage of the latter bar, each of the guard rails is provided with a cut away portion 62 as shown 35 in Fig. 8.

Each of the guard rails is also preferably provided with a cut out portion 63 to permit the electric wires or rods to run from the 40 switch point to a signal pole.

From the foregoing, I believe that the construction, operation and advantages of the present invention will be readily apparent to practical railroad men, and I am aware 45 that various changes may be made in the construction illustrated without departing from the primary purpose of the invention as expressed in the claims.

What I claim and desire to secure by Letters Patent is:

1. In combination, stock rails, movable switch points cooperating with said stock rails, guard rails arranged between the stock rails, and filler blocks arranged between said 55 guard rails and stock rails, each of said filler blocks including flanges with a groove arranged between the same, and the end edges of said flanges being tapered to facilitate the passage of articles through said groove.

60 2. A combination as claimed in claim 1 in which the grooves in the filler blocks have their bottom surfaces tapered downwardly from the central portion of the same to the ends.

65 3. In combination, stock rails, movable

switch points cooperating with said stock rails, guard rails arranged between the stock rails, and cover plates for said guard rails, each of said guard rails consisting of a base, a web rising from said base and having an 70 offset portion, a shoulder arranged at one end of the offset portion, a head carried by said web, and the upper edge of said web tapering downwardly from said head to the ends of the guard rail. 75

4. A combination as claimed in claim 3 in which each of said plates has its end portions tapered downwardly corresponding to the tapered edge of the guard rail.

5. A combination as claimed in claim 3 in 80 which each of said plates is tapered downwardly from its central portion to its ends, and the ends of said plate being provided with flat portions adapted to be secured to the railway ties.

6. A combination as claimed in claim 3 in which each of said plates is provided at one end with a lateral extension provided with an upwardly and outwardly offset portion adapted to permit the flange of a switch 90 point to move beneath the same. 85

7. A combination as claimed in claim 3 in which each of said plates is provided at one end with a flat portion provided with an upwardly and outwardly extending portion having an outwardly tapered edge. 95

8. A combination as claimed in claim 3 in which each of said plates has its outer edge tapered downwardly and outwardly.

9. A combination as claimed in claim 3 in 100 which each of said plates is provided at one end with a flat portion, one extremity of said plate being curved outwardly and merging into said flat portion.

10. A combination as claimed in claim 3 in 105 which each of said plates is provided with a horizontally disposed central portion and horizontally disposed end portions arranged at a lower plane, the plate being curved downwardly from the central portion to the 110 end portions.

11. The combination with a stock rail, a guard rail having a cover plate, and a filler block located between said rails, of a substantially U-shaped clamp provided with an inverted T-shaped recess through which said rails and block extend, said clamp being provided with a step-shaped surface adapted to cooperate with the head of the guard rail and one edge of said cover plate, said clamp being also provided with a groove merging into said recess, and a wedge cooperating with one of said rails and having a rib adapted to engage said groove. 115 120

12. A combination as claimed in claim 3 in 125 which the web of said guard rail is provided with a cut-away portion to permit the passage of a switch-operating bar.

13. A combination as claimed in claim 3 in which the web of said guard rail is pro- 130

vided with a cut-away portion to permit the passage of electric conductors extending to a switch point.

14. In a railway track, stock rails, a plurality of guard rails arranged between the same and having cover plates, and a spacing member arranged between said guard rails and consisting of a flat plate provided at its ends with outwardly extending raised portions adapted to engage the bases of the

guard rails, vertically extending portions projecting from said raised portions and terminating in inwardly extending angular extensions adapted to engage the heads of the guard rails and said cover plates, and vertical reinforcing members integral with said vertically extending portions. ¹⁵

In testimony whereof I affix my signature.

DENNIS E. LAHEY.
